UNITED STATES PATENT OFFICE.

MARK TAFFEL, OF LONDON, ENGLAND.

DESIGN FOR A LINGERIE CLIP.

Application filed January 2, 1925. Serial No. 11,855. Term of patent 14 years.

To all whom it may concern:

Be it known that I, MARK TAFFEL, a subject of the King of Great Britain, residing at 118, Brondesbury Road, London, England, have invented a new, original, and ornamental Design for a Lingerie Clip, of which the following is a specification, reference being had to the accompanying drawing, forming a part thereof.

The lingerie clip is illustrated in perspective and as shown comprises a piece of ribbon or a strip of suitable material having fastening means at its ends for joining the same and a floral representation or decorative pattern between the said ends.

I claim—

The ornamental design for a lingerie clip as shown and described.

MARK TAFFEL.
